GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC OUTLET-FITTING.

1,100,505.

Specification of Letters Patent. Patented June 16, 1914.

Application filed February 5, 1913. Serial No. 746,345.

To all whom it may concern:

Be it known that I, GEORGE B. THOMAS, a citizen of the United States of America, and residing at Bridgeport, in the county 5 of Fairfield and State of Connecticut, have invented a certain new and Improved Electric Outlet-Fitting, of which the following is a specification.

My invention relates to electric outlet fittings and the particular object of my invention is to provide a combination fitting in which a switch and pilot light are provided to respectively control and indicate the condition of the branch circuit which is tapped 15 from the fitting.

The fitting is particularly useful in kitchen or dining room installations in which current is to be tapped from a fitting to an electric iron, for instance, or to an electric 20 toaster, heating pad or the like. In such installations it is extremely desirable that an indicator of a nature to attract attention, such as a ruby bull's-eye light, should be arranged in the branch circuit so that the person 25 using the appliance may be reminded to switch off the current after use and before the heating appliance has become dangerously overheated. Of course the invention is not limited to this particular type of installation or use.

In the accompanying drawings, Figure 1 is a longitudinal vertical section through a fitting of the type above mentioned; Fig. 2 is a plan thereof, with face plate removed; 35 Fig. 3 is an inverted plan; and Figs. 4, 5 and 6 are respectively similar views of a modified form of the fitting.

In the form shown in Figs. 1, 2 and 3 the present fitting comprises an insulating base 40 divided by partitions 11 and 12 into three chambers 13, 14 and 15. A face plate 16 common to the three chambers is arranged upon the base by means of securing screws which pass through the plate and engage 45 the metal ears 17, the latter serving also as the means by which the base may be mounted in a three gang metallic outlet box of common construction diagrammatically represented in Fig. 1, at 18. In the three chambers 13, 14 and 15, I arrange respectively a rotary switch 19, terminals for a bull's-eye lamp 20, and terminals for an attachment plug 21. The rotary switch mechanism may be of any suitable type, preferably provided

with an indicating dial 22 visible through 55 an aperture 23 punched in the face plate. The terminals in chamber 14 to receive the base 24 of the bull's-eye lamp 20 may be of any suitable type, but I prefer clips 25 and center contact spring 26 of the character 60 shown in the copending application of Robert Abbott, Serial Number 731,169. A translucent bull's-eye 27 is mounted in the face plate above the lamp. Similarly the plug terminals may be of any desired character, 65 those here shown at 28—28 being of the character commonly employed for a plug of the Chapman type. Doors 28^a are pivoted in the face plate to admit the plug and close around the neck of the plug after the 70 latter is inserted.

The main wires are electrically connected to the fitting at the integral binding screw and switch terminals 29, 30. The co-operating switch terminals 31 and 32 are electrically connected by screws 33, 34 with straps 35, 36 let into recesses formed in the lower face of the base and extending lengthwise of the latter beneath the bull's-eye and plugging chambers 14 and 15. Current is 80 tapped from these straps to the lamp terminals by screws 37, 38, a lug 39 being formed on the strap 36 and extending to a point beneath the lamp contact 25. Ventilation holes 40 are provided in the base of 85 the lamp chamber to prevent overheating by the lamp. The straps 35, 36 end beneath the plug terminals to which they are electrically connected by the screws 41, 42. It is thus obvious that when the switch is "on" the 90 current is led by these straps 35, 36 to the lamp terminals and to the plug terminals in parallel. Consequently when the switch is "on" and the current is flowing through the plugged branch, there will be constant 95 illumination of the bull's-eye by the lamp and a signal will thus be constantly given to the operator to turn the main switch when through using the plug branch.

The same result is attained in the second 100 exemplary embodiment of my invention illustrated in Figs. 4 to 6 inclusive. The modifications here shown are only those incident to the use of switch and plug mechanisms of types different from those first described. Thus here instead of a rotary switch I employ a push button switch 43 of the type in which the switch mechanism is removable

and the push buttons pass through apertures in the face plate, one of said apertures 44 being shown. Upon the insertion of the switch, the switch terminal plates 45, 46, 5 symmetrically arranged at opposite ends of the switch body, frictionally contact with the wire terminal plates 47, 48 and the coöperating terminals 49, 50 mounted in permanent position on the base. The attachment plug 10 contacts are of the ordinary screw shell 51 and center contact 52 type, while the aperture in the face plate to permit the insertion of the plug 53 is normally closed by the shutter 54. The straps 55, 56 let into the 15 lower face of the base correspond to those previously described, from which they differ only in so far as is necessary to accommodate them to the differently located terminals on the switch and plug receptacle.

20 I am well aware that I am not the first to employ a pilot light in a switch circuit, for instance as shown in Richmond 850,100. Attachment plug outlets in switch controlled circuits are also common, as shown in Rohrer 25 468,474. It has long been customary to mount fuse plugs on the same base and in series with a switch as shown for instance in Gibbons 967,632. Multiple plug outlets have been arranged in parallel on an attachment 30 plug base, as in Hubbell 776,326. I do not claim to be the inventor of any such arrangements—none of which accomplish the end at which I aim. So far as I am aware however, I am the first to invent an outlet box fitting 35 having the structure and characteristics shown in the accompanying drawing and specified in the following claims.

Other modifications and arrangements of the parts will readily suggest themselves and 40 I do not limit myself to the precise details shown.

I claim as my invention:—

1. An electric outlet fitting comprising a one-piece base of substantially uniform 45 depth throughout, vertical webs integral

therewith dividing said base into three electrically insulated chambers, switch, lamp and plug outlet terminal elements mounted respectively in said chambers, wire terminals on said base and connections therefrom to the line terminals of the switch straps let into the lower face of the base and extending longitudinally of the base beneath said chambers, electrical connections from the switch load terminals to said strap, and 55 means for connecting said lamp and plug outlet terminals to said straps in parallel in the switch controlled circuit, substantially as described.

2. An electric outlet fitting comprising a one piece base switch, lamp and plug terminals arranged thereon, wire terminals electrically connected with the line terminals of the switch, and means connecting the load terminals thereof in parallel with the lamp 65 and plug terminals, in combination with a cover plate overlying said fitting and having apertures to permit the passage therethrough of the switch actuating device and a plug connector and carrying also a bull's-eye in 70 register with the lamp terminals.

3. An electrical outlet fitting comprising a one piece base, having three insulated chambers, switch, lamp and plug terminals arranged in said chambers respectively, wire 75 terminals electrically connected with the line terminals of the switch, means connecting the load terminals of the switch in parallel with the lamp and plug terminals and a cover plate common to said chamber and 80 having a bull's-eye overlying the lamp chamber and apertures overlying the switch and plug chambers, for the purpose described.

In testimony whereof I have signed my name to this specification, in the presence of 85 two subscribing witnesses.

GEORGE B. THOMAS.
